DESIGN FOR A FLY SWATTER BLADE

Albert L. Murray, Auburn, Ind.

Application October 29, 1934, Serial No. 53,796

Term of patent 7 years

To all whom it may concern:

Be it known that I, Albert L. Murray, a citizen of the United States, residing at Auburn, in the county of De Kalb and State of Indiana, have invented a new, original, and ornamental Design for Fly Swatter Blade, of which the following is a specification, reference being had to the accompanying drawing forming part thereof.

Figure 1 is a plan view of a fly swatter blade showing my new design and Fig. 2 is an edge elevation.

I claim:

The ornamental design for a fly swatter blade, as shown.

ALBERT L. MURRAY.
